UNITED STATES PATENT OFFICE.

ABRAHAM GOLDKNOPF, OF NEW YORK, N. Y.

COLLAR-STUD SUPPORT.

Application filed November 1, 1922. Serial No. 598,365.

To all whom it may concern:

Be it known that I, ABRAHAM GOLDKNOPF, a citizen of the United States, and a resident of the city of New York, borough of Manhattan, in the county and State of New York, have invented new and useful Improvements in Collar-Stud Supports, of which the following is a full, clear, and exact description.

10 This invention relates to collar stud supports.

Normally the collar stud for attaching a collar to a shirt is located over the thyroid gland. Sometimes, due to the shape of the 15 collar and the neckband of the shirt, the stud is pressed against the isthmus of the thyroid gland. If under normal conditions the collar stud does not bear on the isthmus of the thyroid it is usually projected against 20 the same by the wearer of the stud taking a deep breath or raising his head. Further, if the collar stud bears on the isthmus of the thyroid the collar and the neckband exert pressure on the lobes of the thyroid. The 25 continual pressure or the periodical pressure of the stud or collar on the thyroid gland interferes with the proper functioning of the gland and improper functioning of the gland is injurious to the health.

30 The general object of this invention is the provision of a device designed to eliminate the friction and pressure ordinarily exerted by the collar stud and collar upon the delicate and extremely important thyroid gland.

35 This object is accomplished by providing a curved plate, to the upper end of which the collar stud is attached, and associating with the lower end of the plate, which is adapted to rest on the sternum, means for 40 anchoring it to the clothing, preferably some garment on the lower portion of the body, so that a downward pull is exerted, fulcruming the curved plate on the sternum and projecting the upper end of the plate 45 forward away from the thyroid gland.

This and other objects of the invention will be more clearly understood from the following detailed description and accompanying drawings, in which—

50 Figure 1 is a side elevation of the stud and support positioned on the sternum;

Figure 2 is a vertical section through the supporting plate showing its construction;

55 Figure 3 is a top plan view of the supporting plate and stud.

Referring to the above-mentioned draw-

ings, a plate 10 consisting of two concave sections 11 and 12 has a stud 13 mounted on its upper end. The plate 10 is enclosed in the casing 14 and packing 15 is inserted between the casing wall that seats on the sternum of the wearer and the plate. Attached to the lower end of the plate is an adjustable strap 16. To the lower end of this strap 16 an eye member 17 is attached for engaging a button 18 or the like. In this case the button 18 is so mounted on an undergarment such as drawers.

Referring to Figure 1, the plate 10 is shown in position on the sternum 20 of a 70 wearer and the stud 13 serves to attach the collar 22 to the shirt 21. The lower section of the plate seats on the sternum 20 with the convex side toward the wearer. The convex portion of the lower section of the plate 75 forms a fulcrum at 23 about which the plate may be rocked. When the wearer is in a normal position the strap 16 exerts a pull on the lower end of the plate 10 projecting the upper end of the plate forward, carrying the 80 stud away from the neck 24 and consequently away from the thyroid gland. If the wearer throws his head backward or takes a deep breath the sternum is projected forward and the strap retains the plate 10 85 against upward movement and so it is rocked about its fulcrum point 23, serving to project the stud forward so that it does not press upon the neck. Thus it will be seen that a simple and efficient device has 90 been provided for protecting the thyroid gland from the collar stud or collar so as to allow it to function properly.

I would state in conclusion that while the 95 illustrated example constitutes a practical embodiment of my invention I do not limit myself strictly to the exact details herein illustrated since manifestly the same can be considerably varied without departing from the spirit of the invention as defined in the 100 appended claims.

Claims:

1. In combination with a collar stud, a device for protecting the thyroid gland, comprising a curved plate having its upper end 105 attached to the collar stud, and means provided in conjunction with the curved plate for retaining the upper end spaced from the thyroid gland.

2. A device of the character described for 110 carrying collar button studs, comprising a curved plate for seating on the sternum, said

plate having a collar button stud mounted on its upper end, and an adjustable strap for attaching to the clothing to exert a pull on the plate so as to retain the upper end projected forward.

3. A device of the character described for carrying collar button studs, comprising a curved plate for seating on the sternum of the wearer, a collar stud attached to the upper end of the curved plate, and means attached to the lower end of the plate for rocking it on the sternum to project the upper end of the plate outward.

4. A device of the character described for use in retaining articles of clothing in position on the wearer, comprising a curved plate for seating on the sternum of the wearer, the curved portion engaging the sternum and forming a fulcrum about which they may be rocked, a collar stud attached to the upper end of the plate, and means for attaching the lower end of the plate to the article of clothing to rock the plate on the sternum projecting the upper end away from the neck of the wearer.

ABRAHAM GOLDKNOPF.
